UNITED STATES PATENT OFFICE.

FREDERICK SAGER, OF ROCHESTER, NEW YORK.

DESIGN FOR A MATCH-SAFE.

SPECIFICATION forming part of Design No. 31,027, dated June 20, 1899.

Application filed May 25, 1899. Serial No. 718,256. Term of patent 7 years.

To all whom it may concern:

Be it known that I, FREDERICK SAGER, a citizen of the United States, and a resident of Rochester, in the county of Monroe and State 5 of New York, have invented and produced a certain new and original Design for Match-Safes, of which the following is a specification.

lower edge of the plate A and at right angles to its central longitudinal line, and said cylindrical portion having the orifice B' and the transverse slot B² therethrough. 15

Having described my invention, what I claim, and desire to secure by Letters Patent, 20 is—

The design for a match-safe, as shown and described.

FREDERICK SAGER.
